HAND MICROPHONE

Leo J. Aucoin, Bantam, Conn., assignor to The Gray
Manufacturing Company, a corporation of Connecticut

Application December 13, 1954, Serial No. 33,502

Term of patent 14 years

(Cl. D26—14)

FIG. 1

FIG. 2

FIG. 4

Fig. 1 is a front elevation of a hand microphone showing my new design;

Fig. 2 is a perspective view from one side of the hand microphone;

Fig. 3 is a rear elevation of the hand microphone; and

Fig. 4 is a plan view of the hand microphone.

I claim:

The ornamental design for a hand microphone, as shown.
